UNITED STATES PATENT OFFICE

91,061

DESIGN FOR A ROOFING SHINGLE

Joseph Ray Fife, Toledo, Ohio

Application June 12, 1933. Serial No. 48,379

Term of patent 14 years

To all whom it may concern:

Be it known that I, JOSEPH RAY FIFE, a citizen of the United States, residing at 166 E. Delaware Ave., city of Toledo, in the county of Lucas and State of Ohio, have invented a new, original, and ornamental Design for a Strip Shingle, of which the following is a specification, reference being had to the accompanying drawing, forming part thereof.

The figure is a plan view of a strip shingle, showing my new design.

I claim:

The ornamental design for a strip shingle, as shown.

JOSEPH RAY FIFE.
